PROTECTIVE HEAD GEAR

Jake E. Brown, 517 18th Ave. N. 98122, and James B. Sorenson, 1530 NE. 95th St. 98114, both of Seattle, Wash.

Filed Aug. 27, 1969, Ser. No. 18,870

Term of patent 14 years

Int. Cl. D2—03

U.S. Cl. D2—232

Fig. 1.

Fig. 2.

Fig. 3.

Fig. 4.

FIG. 1 is a side elevation view of a protective head gear showing our new design;

FIG. 2 is a front elevational view of the head gear shown in FIG. 1;

FIG. 3 is a top plan view of the head gear shown in FIGS. 1 and 2; and

FIG. 4 is a front elevational view of a modified form of head gear incorporating our invention.

We claim:

The ornamental design for a protective head gear, substantially as shown and described.

UNITED STATES PATENT OFFICE
Certificate

Patent No. D. 220,376

Patented April 6, 1971

Jake E. Brown and James B. Sorenson

Application having been made by Jake E. Brown and James B. Sorenson, the inventors named in the patent above identified, for the issuance of a certificate under the provisions of Title 35, Section 256, of the United States Code, deleting the name of James B. Sorenson as a joint inventor, and a showing and proof of facts satisfying the requirements of the said section having been submitted, it is this 10th day of August, 1971, certified that the name of the said James B. Sorenson is hereby deleted from the said patent as a joint inventor with the said Jake E. Brown.
